UNITED STATES PATENT OFFICE.

HENRY THOMAS DORAN, OF TORONTO, ONTARIO, CANADA.

AUTOMOBILE DIRECTION-INDICATOR.

1,318,982.

Specification of Letters Patent.

Patented Oct. 14, 1919.

Application filed March 13, 1919. Serial No. 282,256.

To all whom it may concern:

Be it known that I, HENRY THOMAS DORAN, of the city of Toronto, in the county of York, in the Province of Ontario, Canada, have invented certain new and useful Improvements in Automobile Direction-Indicators, of which the following is the specification.

My invention relates to improvements in automobile direction indicators and the object of the invention is to devise simple means which may operate a mechanical hand to place it in various indicating positions extending from the side of a car and it consists essentially of the following arrangement and construction of parts as hereinafter more particularly explained.

Figure 1, is a perspective view of my device showing it attached to the wind shield frame.

Fig. 2, is an enlarged perspective detail partially broken away and in section, showing the parts in the normal position.

Fig. 3, is a similar view to Fig. 2, showing the parts in the position they assume when indicating a "turn to the left."

Fig. 4, is a similar view to Figs. 2 and 3, showing the parts in the position they assume when giving a "turn to the right."

Fig. 5, is a similar view to Figs. 2, 3 and 4, showing the parts in the position they assume indicating "stop."

Fig. 6, is a vertical section through Fig. 2, on a line with the pivot pin 5.

Fig. 7, is a vertical section through Fig. 2, taken on a line with the cam roller 6.

In the drawings like characters of reference indicate corresponding parts in the various figures.

1 indicates a casing which is rectangular in form and set vertically with its outer longitudinal vertical edge open at 1°. 2 indicates a plate secured within the casing and provided with a cam orifice 2°. The opposite longitudinal edge wall of the casing 1 is provided at its lower end with a slotted orifice 1°. 3 indicates an operating bar which extends through such slotted opening and is provided at its outer end with a suitable knob 3° or other device for pushing the bar 3 longitudinally through the orifice 1°. The forward end of the bar 3 is provided with a channel portion 3°.

4 indicates a hand indicator, which is provided at its lower end with a rectangular portion 4° having its lower forward corner

4° rounded off. 5 indicates a pin extending through the channel portion 3° of the bar 3 and through the portion 4 of the hand concentrically with the round portion 4°. One side of the channel bar portion 3° is extended upwardly at 3' in order to form a guiding bearing for the hand 4 during its swinging operation. The opposite wall of the channel bar portion 3° is provided at 3'' with a notch 65 for a purpose which will hereinafter appear.

6 indicates a cam roller which is carried by the lower portion of the hand 4 at the opposite side to the pivot pin 5, such cam roller engaging the edge of the cam orifice 2°. The cam orifice 2° is provided with a horizontal lower edge 2' terminating at its inner end in an upwardly and outwardly inclined portion 2° from which extends an upwardly curved portion 2° which is concentric with the center of the pin 5. From the outer end of the curved portion 2° the edge of the orifice extends in an inclined direction inwardly and downwardly at 2° terminating in a shoulder 2° from which extends an outwardly inclined portion 2° meeting the opposite end of the horizontal edge 2' of the cam orifice 2.

When the device is to indicate a "stop" position the bar 3 is forced outwardly until it assumes the position shown in Fig. 5. If it is desired to indicate a "turn to the left", the bar 3 is then drawn sharply inward so that the cam roller first engages the inclined portion 2° and is carried upwardly tilting the hand 4 outwardly so that when the cam roller 6 reaches the upper end of the inclined portion 2° the hand overbalances so as to drop to a horizontal position, the cam roller 6 following the concentric curved edge 2° assuming the position shown in Fig. 3.

When it is desired to indicate a "turn to the right" the bar 3 is again forced outwardly carrying the pivot point 5 in a similar direction and thereby forcing the cam roller 6 to travel down the inclined portion 2° of the cam orifice thereby drawing the hand upwardly into an inclined position until it passes the shoulder 2° thereby definitely locking it in such position, preventing its return movement.

In order to return it to normal the hand is taken up to the vertical position by further outward movement of the bar 3 and then by a return movement drawn into the casing 1.

From this description it will be seen that I have devised a very simple device where-

by all indicating signals necessary are given by a mechanical hand which may be readily operated by the driver of a car from the center of the car or any position adjacent to the 5 steering wheel.

What I claim as my invention is:

1. An automobile direction indicator comprising a casing having a vertical edge opening, a push bar extending through the opposite edge of the casing at the bottom, a hand pivotally mounted upon the push bar in proximity to its front lower corner, a cam roller carried by the rear lower corner of the hand, a cam plate secured within the 10 interior of the casing and having a cam orifice formed with a horizontal lower edge terminating in an upwardly outwardly inclined portion, and an arc-shape edge concentric with the center of the hand pivot when in 15 the normal position and having the forward edge of the orifice inclined inwardly from the top and the bottom.
- 20 the normal position and having the forward edge of the orifice inclined inwardly from the top and the bottom.

2. An automobile direction indicator comprising a casing having a vertical edge opening, a push bar extending through the opposite edge of the casing at the bottom, a hand pivotally mounted upon the push bar in proximity to its front lower corner, a cam roller carried by the rear lower corner of the hand, a cam plate secured within the 25 interior of the casing and having a cam orifice formed with a horizontal lower edge terminating in an upwardly outwardly inclined portion, and an arc-shape edge concentric with the center of the hand pivot when in 30 the normal position and having the forward edge of the orifice inclined inwardly from the top and the bottom, the inwardly inclined upper and lower portions having a shoulder interposed therebetween.

HENRY THOMAS DORAN.
